LIFT

Raymond C. Boone, Grafton, N. Dak.

Application October 14, 1947, Serial No. 779,771

4 Claims. (Cl. 187—9)

1

This invention relates to a lift, and more particularly, to a lift for produce to be piled or stacked in a warehouse or the like.

A primary object of this invention is the provision of an automatic lift characterized by a continuously operated chain lift or the like, adapted vertically to reciprocate an elevator, and having means providing an automatic stop at the top and bottom of the device.

An additional object of the invention is the provision of such a device which is sturdy and durable in construction, reliable and efficient in operation, and relatively simple and inexpensive to manufacture, assemble and utilize.

Other objects will in part be obvious, and in part be pointed out as the description of the invention proceeds, and shown in the accompanying drawings, wherein there is disclosed a preferred embodiment of this inventive concept.

In the drawings:

Figure 1 is a side elevational view of one form of lift embodying features of the instant invention.

Figure 2 is a rear elevational view of the device shown in Figure 1.

Figure 3 is a perspective of the elevator mechanism disassociated from the lift.

Figure 4 is a sectional view, partially broken away, taken substantially along the line 4—4 of Figure 2.

Similar reference characters refer to similar parts throughout the several views of the drawings.

Referring now to the drawings in detail, the device of the instant invention comprises a base, generally indicated at 10, which may be formed of channel iron or the like in the form of a rectangle, from which front uprights 11 extend upwardly a desired distance. Uprights 11 are braced by angularly inclined rear uprights 12 connected to uprights 11 by transverse reinforcing members 13, and angularly inclined supplemental reinforcing members 14. The upper extremity of the lift may include a plate 15, across which extends a transverse bar 16 connected, as by cross-cables 17, or the like, to a rear reinforcing member 18.

The base 10 carries a suitable electric motor 20, provided with a drive shaft 21, upon which is mounted a sprocket 22, which drives, through a chain 23, a sprocket 24, mounted on a shaft 25, which extends transversely of the base adjacent the uprights 11, and which carries spaced sprockets 26 adjacent opposite ends thereof, each of which drives a chain 27, which extends verti-

2

cally adjacent front uprights 11, the upper extremities of the chains being mounted on stub axles 30, carrying sprockets 31 adjacent the top 15 of the device.

5 The chains 27 have positioned thereacross and secured thereto a single transverse bar 35, adapted to engage and operate a lift member generally indicated at 36.

As best shown in Figure 3, lift member 36 includes right angled members 37, to which are secured a vertical plate 38, an angle plate 39, and a horizontal lift-supporting plate 40. Secured across the top of the members 37 is a bar 41, provided at its extremities with roller guides 42, 15 while secured in the angle of members 37 is a second bar 43 also provided at its extremities with rollers 44.

As best shown in Figure 1, the rollers 44 are adapted to ride on the front surfaces of angle 20 iron uprights 11, while, as best shown in Figure 4, the rollers 42 are adapted to engage the rear surfaces thereof. Extending rearwardly from the upper extremity of the member 36 are a pair of spaced bars 46, each provided at its extremity 25 with a depending portion 47, the bars 46 being adapted to be engaged by the transverse bar 35 as the same is moved upwardly, and/or downwardly, by the chains 27.

From the foregoing, the operation of the device 30 should now be readily understandable. The motor 20 is energized, which occasions continuous rotation of chains 27 about sprockets 26 and 31. As the bar 35 engages beneath the bars 46 carried by the lift structure 36, it will be apparent 35 that the device is elevated, traveling in the channels formed by the uprights 11. When the device reaches the top, there is a perceptible pause during the passage of bar 35 over sprockets 31 sufficient to permit unloading of the device; and, 40 conversely, when the bottoms of the angle members 37 rest upon the base 10, there is a further perceptible pause on the downward motion of the bar, while the bar continues to travel about the sprockets 26, and thence upwardly until such 45 time as it re-engages the bars 46, whereupon the lift of elevator 36 is resumed.

From the foregoing it will now be seen that there is herein provided an improved automatic lift, which accomplishes all the objects of this 50 invention, and others, including many advantages of great practical utility and commercial importance.

As many embodiments may be made of this inventive concept, and as many modifications 55 may be made in the embodiment hereinbefore

3

shown and described, it is to be understood that all matter herein is to be interpreted merely as illustrative and not in a limiting sense.

I claim:

1. In an automatic lifting device, an upstanding frame, wheels mounted upon the upstanding frame near its top and bottom, an endless element passed about the wheels, a lift mounted upon the frame to travel longitudinally thereof near the endless element, a generally horizontal bar secured to the lift and projecting transversely across the endless element and having a length approximately equal to the diameter of the wheels, and an operating element mounted upon one run of the endless element and slidably engaging the lower face of the bar to travel longitudinally of the bar.

2. In an automatic lifting device, an upstanding frame, transverse pairs of wheels mounted upon the frame near its top and bottom, endless flexible elements passed about the wheels, a lift mounted upon the frame to travel longitudinally thereof near the endless elements, generally horizontal bars secured to the lift and projecting transversely across the endless elements and having a length approximately equal to the diameter of the wheels, a substantially horizontal rod mounted upon corresponding runs of the endless elements and slidably engaging the lower face of the bars to travel longitudinally of the bars, and means connected with one pair of wheels to drive the same.

3. In an automatic lifting device, an upstanding frame, a substantially horizontal shaft mounted upon the lower portion of the frame, spaced wheels mounted upon the shaft, upper spaced wheels mounted upon the frame and having the space between them unobstructed, flexible endless elements engaging corresponding upper and lower wheels, a lift slidably mounted upon the frame to travel longitudinally thereof near the endless elements, generally horizontal bars secured to the upper portion of the lift and extending between and across the endless ele-

4

ments and having a length at least as great as the diameter of the wheels, a substantially horizontal rod mounted upon corresponding runs of the flexible elements and slidably engaging the lower faces of the bars to move longitudinally thereof, and means connected with the shaft to drive the same.

5. In an automatic lifting device, an upstanding frame including rails, a substantially horizontal shaft mounted upon the lower portion of the frame, spaced wheels mounted upon the shaft, upper spaced wheels, means connected with the frame to mount the upper wheels upon the frame and not projecting inwardly beyond such wheels for any considerable distance so that the space between such wheels is uninterrupted, flexible endless elements engaging corresponding upper and lower wheels, a lift to travel longitudinally of the frame near the endless elements, wheels mounted upon the upper portion of the lift and engaging the inner faces of the rails, wheels mounted upon the lower portion of the lift and engaging the outer faces of the rails, generally horizontal bars secured to the upper portion of the lift and projecting transversely between and across the endless elements and having a length at least as great as the diameters of the wheels which engage the endless elements, a substantially horizontal rod secured to corresponding runs of the endless elements and slidably engaging beneath the bars to move longitudinally thereof, and means connected with the shaft to drive it.

RAYMOND C. BOONE.
